ABSTRACT OF THE DISCLOSURE

Disazo compounds containing two thiazolyl-azo-aniline moieties joined by the group $-\text{CH}_2\text{CH}_2\text{SO}_2\text{CH}_2\text{CH}_2-$ which is attached to the nitrogen atom of each aniline coupling component. The disazo compounds are useful as dyes for hydrophobic textile materials.

This invention relates to novel water insoluble, symmetrical and unsymmetrical disthiazolylazo compounds and, particularly, to disthiazolylazo dyes for hydrophobic textile fibers, yarns and fabrics.

The disthiazolylazo compounds of the invention are characterized by the general formula

wherein R represents a thiazolyl radical having the structure

wherein X represents hydrogen, alkyl, e.g. methyl, ethyl; substituted alkyl such as halogenoalkyl, e.g. chloromethyl, trifluoromethyl, cyanoalkyl, e.g. cyanoethyl, nitroalkyl, e.g. nitroethyl, hydroxylalkyl, e.g. hydroxyethyl; alkoxy, e.g. methoxy; alkanoylaminio, e.g. acetamido; nitro; halogeno, e.g. chloro, bromo; cyano; alkylsulfonyl, e.g. methylsulfonyl; substituted alkylsulfonyl, e.g. cyanoethylsulfonyl; carbamoyl; aryl, e.g. phenyl; benzamido; benzylamino; N-alkylbenzylamino, e.g. N-phenylmethylamino; alkoxy carbonyl, e.g. ethoxycarbonyl; hydroxyl; alkanoyl, e.g. acetyl; formyl; sulfamoyl; N-alkylsulfamoyl; alkylsulfonamido, e.g. methylsulfonamido, ethylsulfonamido; dialkylsulfonamido, e.g. dimethylsulfonamido, dicarboxylic acid imido, e.g. succinimido; thiocyanato; alkylthio, e.g. methylthio; benzoxy; benzoyl; combinations thereof; and m represents 0, 1 or 2;

R^1 and R^4 may be the same or different and represent monocyclic carbocyclic aromatic groups of the benzene series having the structure

wherein Y may be the same or different in R^1 and R^4 and represents hydrogen, alkyl, e.g. methyl, ethyl; alkoxy, e.g. methoxy; alkanoylaminio, e.g. acetamido; halogeno, e.g. chloro, bromo; benzamido; alkylsulfonamido, e.g. methylsulfonamido, ethylsulfonamido, combinations thereof; and n represents 0, 1, 2 or 3.

Preferably, the alkyl radicals of the substituents represented by Y are lower alkyl, e.g. from 1 to about 4 carbon atoms.

R^2 and R^3 may be the same or different and represent hydrogen or an alkyl radical, preferably lower alkyl, i.e.

2

from 1 to 4 carbon atoms, being unsubstituted or substituted such as hydroxyalkyl, e.g. hydroxyethyl, polyhydroxyalkyl, e.g. 2,3-dihydroxypropyl, alkoxyalkyl, e.g. methoxyethyl, cyanoalkyl, e.g. cyanoethyl, cyanoalkoxyalkyl, e.g. β -cyanoethoxyethyl, alkanoyloxyalkyl, e.g. acetoxymethyl, alkoxy carbonylalkyl, e.g. ethoxycarbonylalkyl, halogenoalkyl, e.g. chloroethyl, α -chloropropyl, bromoethyl, hydroxyhalogenoalkyl, e.g. β -hydroxy- α -chloropropyl, alkylsulfonylalkyl, e.g. methylsulfonylalkyl, alkyl- $\text{OCOOCH}_2\text{CH}_2-$ e.g. $\text{CH}_3\text{OCOOCH}_2\text{CH}_2-$, carbamoylalkyl, e.g. carbamoylethyl; alkylcarbamoylalkyl, e.g. ethylcarbamoylethyl; dicarboxylic acid imidoalkyl, e.g. succinimidoethyl; aryl, e.g. benzyl; phenoxyalkyl, e.g. β -phenoxyethyl; alkylsulfonamidoalkyl, e.g. methylsulfonamidoethyl; carbamatoalkyl, e.g. carbamatoethyl; and the like.

The disthiazolylazo compounds of the invention are prepared by coupling the conventional diazonium salts of compounds having the formula

with unsymmetrical coupling components having the formula

wherein R^1 and R^4 may be the same or different and R^2 and R^3 may be the same or different but either R^1 must be different from R^4 or R^2 must be different from R^3 or with symmetrical coupling components having the formula

wherein $\text{R}^1=\text{R}^4$ and $\text{R}^2=\text{R}^3$ and wherein R, R^1 , R^2 , R^3 , and R^4 are defined as set forth above with reference to Formula I.

The unsymmetrical couplers of Formula III are prepared by reacting one mole of an appropriately substituted aryl amine with one mole of divinylsulfone in the presence of a catalyst such as acetic acid and contacting the reaction product, a vinylsulfonylethyl arylamine, with one mole of a different aryl amine, as set forth in the following illustrative sequence:

65 wherein Ar and Ar^1 represents either R^1 or R^4 of Formula I wherein R^1 and R^4 are the same or different and R^2 and R^3 are the same or different but either R^1 must be different from R^4 or R^2 must be different from R^3 and are defined as set forth in Formula I.

70 The symmetrical couplers of Formula IV are prepared by reacting two moles of an appropriately substituted aryl amine with one mole of divinylsulfone in the presence of

acetic acid catalyst, as set forth in the following illustrative sequence:

wherein $\text{Ar} = \text{R}^1 = \text{R}^4$ and $\text{R}^2 = \text{R}^3$ and wherein R^1 , R^2 , R^3 and R^4 are defined above in Formula I.

The following examples will serve to illustrate the preparation of representative couplers and disthiazolylazo compounds of the invention. As will be seen from the examples, the substituents X, Y, R² and R³ set forth in For-

mula I serve primarily as auxochrome groups to control the color of the disthiazolylazo compound.

Preparation of symmetrical couplers

Preparation of bis[2-(N-ethyl-m-toluidino)ethyl]sulfone.—A mixture of 27.0 g. N-ethyl-m-toluidine, 11.8 g. divinylsulfone, 5 cc. glacial acetic acid, and 50 cc. toluene was refluxed for 24 hrs. The toluene and acetic acid were removed under vacuum and the residue taken up in 150 ml. of ethanol. This solution was chilled for 2 hrs. at near 0° C. and the white crystalline product was collected by filtration. Yield: 21.4 g. M.P. 58–61°. It had the structure:

Example 2.—Nitrosyl sulfuric acid was prepared by dissolving 1.62 g. NaNO_2 in 12 ml. conc. H_2SO_4 below 80° C. The solution was cooled to 15° and 25 ml. 1:5 acid was added below 20° C. After further cooling to -2°, 5.60 g. 2-amino-5-bromothiazole hydrobromide was added below 3° C. followed by 25 ml. 1:5 acid below 5° C. After stirring for 1½ hr. at -5 to +5° C. the solution was added to 4.20 g. of coupler B in 25 ml. 1:5 acid chilled in an ice water bath. The solution was neutralized with ammonium acetate to brown on Congo red paper and after 1 hr. drowned in water. The precipitated dye was filtered, washed with water and air dried. It dyed polyester and cellulose acetate red-violet shades and showed excellent sublimation fastness on polyester fibers. It had the formula:

Preparation of bis[2-(N- β -hydroxyethyl-m-toluidino)ethyl]sulfone.—The above procedure was repeated, sub-

stituting N- β -hydroxyethyl-m-toluidine for N-ethyl-m-toluidine for N-ethyl-m-toluidine. The product had the structure:

60

60 Example 4.—A diazonium solution was prepared from
4.96 g. 2-amino-5-bromothiazole hydrobromide as in Ex-
ample 2 and added to a solution of 3.88 g. of coupler A
in 25 ml. 1:5 acid. The dye was obtained in the manner
65 described in Example 2. It gave red shades on polyester
and cellulose acetate fibers which showed outstanding
sublimation fastness. It had the formula:

Example 5.—A diazonium solution was prepared from 4.00 g. of 2-amino-5-thiocyanato-thiazole according to the procedure of Example 38. It was added to a solution of 3.88 g. bis [2-(N-ethyl-m-toluidino)ethyl]sulfone in 25 ml. 1:5 acid. The dye was completed as in Example 38 and gave red-violet dyeings on cellulose acetate and polyester fibers showing excellent sublimation fastness on the latter. It had the formula:

Example 6.—Nitrosylsulfuric acid was prepared from 1.44 g. NaNO_2 and 10 ml. concentrated H_2SO_4 below 15 80°C . The solution was cooled to 15°C and 20 ml. 1:5 acid added below 20°C . The solution was further cooled to 0°C , and 2.00 g. 2-aminothiazole was added. After stirring for 1.5 hours at -5°C . to $+5^\circ\text{C}$. the solution was added to a solution of 3.88 g. bis[2-(N-ethyl-m-toluidino)ethyl]sulfone in 25 ml. 1:5 acid. Neutralization to a brown color on Congo Red paper with ammonium acetate was followed by coupling for 2 hours. The reaction mixture was drowned in water and the precipitated dye filtered and washed with water. It dyed cellulose acetate and polyesters red shades with excellent sublimation fastness on polyesters. The dye had the formula:

The disthiazolylazo compounds illustrated in the following table are prepared by the procedure illustrated in Examples 1 through 6, above. Thus, the appropriate compounds of Formula II are coupled with suitable compounds of Formula IV to obtain the compounds of Formula I wherein, $\text{R}^1=\text{R}^4$, $\text{R}^2=\text{R}^3$ and the thiazolylazo groups are identically substituted.

25 A mixture 25.3 g. N-ethyl-N- β -vinylsulfonylethyl-m-toluidine, 15.5 g. N-ethyl-m-chloroaniline, 5 ml. acetic acid and 50 ml. toluene was refluxed for 24 hrs. The toluene and acetic acid were removed under

35 residue crystallized from ethanol. The product had the structure:

A mixture 29.9 g. 2,5-dimethoxy-N-ethyl-N- β -vinylsulfonyl-ethylaniline, 13.7 g. N- β -hydroxyethylaniline, 5 ml. acetic acid and 50 ml. toluene was refluxed together for 24 hrs. The toluene and acetic acid were removed under

35 reduced pressure and the viscous oil obtained was used without further purification. The coupler had the formula:

Coupler D

				Violet.

Preparation of unsymmetrical dyes

Example 37.—An amount of 2.90 g. 5-nitro-2-aminothiazole was dissolved in 25 ml. of water and 13.5 ml. conc. H_2SO_4 . This solution was cooled to $-10^\circ C$. and 1.54 g. $NaNO_2$ in 10 ml. conc. H_2SO_4 was added below $0^\circ C$. The solution was stirred 10 min. and added to a solution of 4.08 g. of coupler C in 25 ml. 1:5 acid. After 30 min. the solution was drowned in water. The precipitated dye was filtered, washed with water and air dried. It dyed polyesters, cellulose acetate and nylon bright red-dish blue shades. It showed excellent sublimation fastness when dyed on polyesters and had the formula:

Example 38.—An amount of 1.62 g. sodium nitrite was added to 12 ml. conc. H_2SO_4 below $80^\circ C$. The solution was cooled to $10^\circ C$. and 25 ml. 1:5 acid added below $20^\circ C$. After further cooling to $-10^\circ C$., 4.00 g. 2-amino-4-methyl-5-thiocyanothiazole was added followed by an additional 25 ml. 1:5 acid. After stirring at -5° to 3° for $1\frac{1}{4}$ hr. in the solution was added to 4.36 g. of coupler D. in 20 ml. 1:5 acid. The reaction mixture was neutralized to brown on Congo red paper with ammonium acetate and allowed to couple 2 hr. The solution was drowned in water and the precipitated dye was filtered, washed with water and air dried. It dyed polyester fibers red-violet shades having excellent sublimation fastness. It had the formula:

The disthiazolylazo compounds illustrated in the following Table are prepared by the procedure of Examples 37 and 38. Thus the appropriate compounds of Formula II are coupled with suitable couplers of Formula III to obtain the compounds of Formula I wherein $R^1 \neq R^4$, R^2 and R^3 can be the same or different and the thiazolylazo groups are identically substituted.

applied thereto by conventional dye methods. The compounds have high affinity for cellulose ester, polyester, and nylon fibers. When the disthiazolylazo compounds are used for dyeing such hydrophobic materials, they should be free of water-solubilizing groups such as sulfo and carboxyl. In general, the dyes have excellent fastness, for example, to light, washing, gas (atmospheric fumes) and sublimation. The dyes are outstandingly sublimation resistant on polyesters.

10 As described above, the present compounds have the characteristic structure of Formula I. This distinctive structure imparts unexpected properties to the compounds,

including the above-described light fastness and sublimation resistance. Thus, we have found the compounds of the invention to have excellent properties as dyes when tested by methods such as described in the A.A.T.C. Technical Manual, 1964 edition.

The compounds of the invention can be used for dyeing hydrophobic fibers such as linear polyester, cellulose ester, acrylic, polyamide, etc., fibers in the manner described in U.S. Patents 2,880,050, 2,757,064, 2,782,187 and 2,043,827. The following example illustrates a method by which the compounds of the invention can be used to dye polyester textile materials.

0.1 g. of the dye is dissolved in the dye pot by warming in 5 cc. of ethylene glycol monomethyl ether. A 2% so-

40 dium-N-methyl-N-oleyl taurate and 0.5% sodium lignin sulfonate aqueous solution is added, with stirring, until a fine emulsion is obtained. Water is then slowly added to a total volume of 200 cc. Then, 3 cc. of "Dacronyx" (a chlorinated benzene emulsion) are added and 10 grams of a textile fabric made of "Kodel" polyester fibers are entered. The fabric is worked 10 minutes without heat and

Ex.	X	R ¹	R ²	R ³	R ⁴	Color
39	5-NO ₂	m-Tolylene	—C ₂ H ₅	—C ₂ H ₄ OH	Phenylene	Violet.
40	4-CF ₃	m-Chlorophenylene	—C ₂ H ₄ CN	—CH ₂ CH ₂ N 	m-Tolylene	Red.
41	4-CH ₃	o-Chlorophenylene	H	CH ₂ CH ₂ OCONH 	do	Red.

43	4-NHCOC ₂ H ₅	2-OCH ₃ -5-CH ₃ phenylene	CH ₂ CH ₂ Cl	C ₂ H ₅	do	Red.
44	None	2-OCH ₃ -5-NHCOC ₂ H ₅ phenylene	CH ₂ CH ₂ OCH ₃	C ₂ H ₅	do	Red.
45	4-CH ₃ , 5-C(=O)CH ₃	m-OCH ₃ phenylene	CH ₂ CH ₂ OOCOCH ₃	C ₂ H ₅	do	Red.
46	5-CN	Phenylene	CH ₂ CH ₂ N 	C ₂ H ₅	do	Violet.
47	5-SCN	m-Cl phenylene	CH ₂ CH ₂ CO ₂ C ₂ H ₅	C ₂ H ₅	do	Red.
48	5-Br	do	CH ₂ CH ₂ Br	C ₂ H ₅	do	Red.
49	5-SO ₂ CH ₃	do	CH ₂ CH ₂ SO ₂ CH ₃	C ₂ H ₅	do	Red.
50	4-phenyl	do	CH ₂ CH ₂ CONH ₂	CH ₂ CH ₂ CONH ₂	do	Red.

The disthiazolylazo compounds of the invention can be used for dyeing textile materials, including protein and synthetic polymer fibers, yarns and fabrics, giving a variety of fast brilliant red to blue shades, including violet, when

then for 10 minutes at 80° C. The dye bath is then brought to the boil and held at the boil for one hour. Following this, the fabric is rinsed in warm water, then 75 scoured in aqueous 0.2% soap, 0.2% soda ash solution.

9. A compound as defined in claim 1 having the formula

10. A compound as defined in claim 1 having the formula

11. A compound as defined in claim 1 having the formula
